UNITED STATES PATENT OFFICE.

HARRISON D. FLEGEL, OF RACINE, WISCONSIN, ASSIGNOR TO EDWARD J. SCHOWALTER, OF RACINE, WISCONSIN.

SPRING-HINGE.

1,135,274.

Specification of Letters Patent.

Patented Apr. 13, 1915.

Application filed May 8, 1914. Serial No. 837,116.

To all whom it may concern:

Be it known that I, HARRISON D. FLEGEL, a citizen of the United States, and resident of Racine, in the county of Racine and State 5 of Wisconsin, have invented certain new and useful Improvements in Spring-Hinges; and I do hereby declare that the following is a full, clear, and exact description thereof.

My invention relates to spring-hinges such 10 as are especially designed to facilitate the hanging and taking down of doors, a member of each hinge being a fixture for permanent connection with a stationary support and with which one of the leaf-members of 15 the hinge has detachable connection, the other leaf-member of said hinge being attachable to a swing-part.

The object of my invention is to provide 20 simple, economical and efficient hinges, similar to those aforesaid, especially adaptable for connection with jambs of door casings having outside molding.

A further object of my invention is to 25 provide for guarding against separation of leaf and fixture members of the hinges without the employment of a tool, and said invention consists in what is herein particularly set forth with reference to the accompanying drawings and pointed out in the 30 claims of this specification.

Figure 1 of the drawings represents a partly sectional side elevation of a full open partly broken spring-hinge in accordance with my invention connecting a swing-part 35 with a stationary support, the plane of the section being indicated by line 1—1 in Fig. 2, and Figs. 2 and 3, horizontal sectional views respectively indicated by lines 2—2 and 3—3 in Fig. 1, the hinge being shown 40 held open in Fig. 3, to permit of a separation of the swing-part from the stationary support.

Referring by numerals to the drawings, 4 indicates the fixture member of my 45 improved spring-hinge, the same being shown in a rabbet of a jamb 5 of a door-casing to which it is fastened by screws. The fixture is shown outwardly flanged at its ends, and parts of the flanges, separated by kerfs from 50 the remainder thereof, are bent to form guide-lugs 6 in which to slide a leaf-member 7 of the hinge. Intermediate of its ends, the fixture is shown as having a hook-lug 8 at the inner edge thereof, and registrable 55 with said hook-lug is a slot 9 in the hinge-

leaf 7. The knuckles 10 of said hinge-leaf 7 are crimped fast on a tubular pintle 11 or otherwise rigid therewith, and the knuckles 12 of the other leaf-member 13 of the hinge are loose on the pintle. 60

Arranged on the pintle, between the knuckles 12, is a spiral spring 14 under tension, its ends being in contact with the leaf-members 7, 13 of the hinge, the fixture-member 4 of said hinge being notched at 4' to 65 clear one end of the spring.

A rod 15 in sliding engagement with the bore of the pintle 11 has a crook-end 15' terminating in a lateral offset 15'', the rod being held in vertically adjusted position by 70 frictional contact thereof with said pintle. Slight upsetting of what is shown as the lower end of the rod will prevent it from being pulled out of the pintle. In practice it is immaterial which end of said rod is 75 uppermost, but its crook-end must be clear of the hinge-leaves except at such times as it is desirable to separate the hinge-member 7 from the fixture member of the hinge.

The leaf-member 13 of the hinge is shown 80 approximately right-angular in cross-section and fastened to a fragment of a door 16, there being partial butt-facing of said leaf-member with the leaf-member 7 of said hinge when the door is closed, as shown by 85 full lines in Fig. 2, but, as indicated by dotted lines in Figs. 2 and 3, the leaf 13 may be straight to provide a full butt-hinge without departure from my invention, as herein claimed, the partial or full butt hinge 90 being applicable to a door-casing jamb having outside molding 17. It is also within the scope of my invention, as herein claimed, to have both leaves 7 and 13 straight and extending in opposite directions from the 95 pintle to form a surface hinge, the fixture-member of said hinge being suitably disposed on flat surface of a stationary support in the form of a door-casing jamb or otherwise, and the hinge-leaf 13 attached to a 100 door or other swing part.

The engagement of the hinge-leaf 7 with the fixture 4 applied to a stationary support is maintained by the expansive force of the spring 14, and a fastening screw 18 of said 105 fixture being run out, by a screw-driver engaging its head-kerf through an opening 19 (of less diameter than the screw-head) provided in said leaf, the leaf-slot 9 will be caused to engage the fixture-lug 8, as shown 110

in Figs. 2 and 3. This being done, the hinge leaf 7 cannot be separated from the fixture 4 until the screw 18 is retracted, whereby a guard is had against ready malicious or mischievous removal of the swing-part from the stationary support. The screw 18 being driven full in, and it is desirable to separate the leaf-member 7 from the fixture-member 4 of the hinge, the rod 15 is adjusted to bring its crooked and laterally offset end intermediate of both leaves of said hinge. This being done, the pressure of the spring 14 on the fixture 4 through the hinge-leaf 7 is overcome and said leaf may be slipped out of engagement with the guide-lugs 6 of said fixture, the result being a separation of the swing-part from the stationary support.

I claim:

20 1. A hinge comprising a tubular pintle, a pair of leaves having knuckles thereof engaged by the pintle, a spring under compression on the pintle and opposed at its ends to the leaves, a rod slidable in the pintle and fashioned at one end for interposition between the leaves, and a plate having guides with which one of the leaves has detachable sliding engagement, the other leaf being attachable to a swing-part and said plate

attachable to a stationary support to constitute a fixture thereon. 30

2. A hinge comprising a plate attachable to a stationary support and provided with end guides, as well as with a hook-lug projecting outwardly from its inner edge, the 35 plate constituting a fixture attachable to a stationary support; a tubular pintle, a pair of leaves having knuckles thereof engaged by the pintle, one of the leaves being slidable in said guides and provided with a slot 40 registerable with said hook-lug, as well as with an opening through which an attaching screw of said plate may be run out to effect an engagement of the leaf-slot with the aforesaid hook-lug; the other leaf being 45 attachable to a swing-part; a spring under tension on the pintle and opposed at its ends to the leaves, and a rod slidable in the pintle and fashioned at one end for interposition between said leaves. 50

In testimony that I claim the foregoing I have hereunto set my hand at Racine in the county of Racine and State of Wisconsin in the presence of two witnesses.

HARRISON D. FLEGEL.
